CLAIM

The ornamental design for a lighting fixture, as shown and described.

DESCRIPTION

FIG. 1 is a top, front left perspective view of the lighting fixture showing my design;

FIG. 2 is a left view thereof;

FIG. 3 is a right view thereof;

FIG. 4 is a front view thereof;

FIG. 5 is a rear view thereof;

FIG. 6 is a bottom plan view thereof; and,

FIG. 7 is a top plan view thereof.

The broken lines shown in the drawings represent portions of the lighting fixture that form no part of the claimed design.

1 Claim, 6 Drawing Sheets
